UNITED STATES PATENT OFFICE.

ABRAHAM B. BARNETT, OF ROANOKE, VIRGINIA.

MEANS FOR TESTING TRACK CIRCUITS.

Application filed December 10, 1923. Serial No. 679,771.

To all whom it may concern:

Be it known that I, ABRAHAM B. BARNETT, a citizen of the United States of America, residing at Roanoke, in the county of Roanoke and State of Virginia, have invented certain new and useful Improvements in Means for Testing Track Circuits, of which the following is a specification.

This invention relates to devices for testing and locating faults in electric circuits, and more particularly in circuits composed principally of the rails of a railroad track.

In railway block signal systems, such as are in common use at the present time, the track rails are divided by means of insulated joints into sections or "blocks" of a mile or more in length, and each rail constituting such block is rendered electrically continuous throughout its length, by means of bonds bridging each rail joint. These bonds are in the nature of short copper conductors, riveted or otherwise secured to the rail ends,

A source of current is connected across the rails at one end of the block, and a track relay, controlling a wayside signal, is connected across the rails at the other end of the block, so that a completely closed circuit, including both rails of the block, is formed, in which circuit current continuously flows from the source of current through one track rail, through the track relay and back through the other track rail to the source of current. The source of current may be either a track battery, where direct current is employed, or a low voltage transformer, in cases where alternating current is used.

In practice, it often happens that the above described track circuit becomes interrupted by reason of a broken rail, or a corroded, loose or broken bond, and when this occurs, the wayside signal remains in the stop or danger position, thus frequently delaying traffic and causing great inconvenience. Heretofore, in order to locate the break or defect in the track circuit, it has been necessary for an inspector to traverse the block on foot, and examine and test each joint and bond to find out just where the defect is. This, of course, is a tedious and time consuming operation.

The primary object of the present invention is to provide testing apparatus in the nature of a small car, so constructed and arranged that it can be simply run over the block of track which is out of order, and will indicate to the operator the exact location of the defect or fault, by means of a signal brought into action immediately that the car passes over the point which is causing the trouble. A further object is to provide means for automatically bringing the car to a stop when it encounters a broken or loose connection in either rail, such as would interrupt the continuity of the track circuit, thus serving as an additional and positive indication of the location of the trouble.

In order that the invention may be readily understood, reference is had to the accompanying drawings, forming part of this specification, and in which:

Figure 1 is a side view of a small motor driven car, equipped with testing instruments, in accordance with my invention;

Figure 2 is an end elevation thereof;

Figure 3 is a diagrammatic plan view of a fragment of track, with the wheels of the car resting thereon, and showing the instruments and circuits which I preferably employ;

Figures 4 and 5 are a cross-section and side elevation, respectively, of one of the wheels with which the car is equipped;

Figure 6 is a fragmentary end elevation of one of such wheels, showing the manner in which it may be insulated from the other wheels and the rest of the car frame; and

Figure 7 is a diagrammatic view showing, on an enlarged scale, my improved means for stopping the car and giving a visual signal when a defect in the track circuit is encountered.

Referring to the drawings in detail, I have illustrated, in Figures 1 and 2, a car of the type commonly employed on railroads by inspectors, and comprising a frame in which are journaled two main wheels 23, and two smaller auxiliary wheels 3. One of the main wheels is driven by means of an internal combustion engine 4. 5 designates the seats for the operator and inspector, and 6

indicates the control lever, by means of which the car is operated.

The wheels 3, of cars of the type illustrated, are usually made as shown in Figures 4 and 5, comprising a metal rim, a metal hub 3^b, and a web 3^a formed of a wooden disc. In order to adapt these wheels for use in connection with my present invention, I attach a conducting strip 15, to the wheel, such strip extending from the rim to the hub, and forming an electrical connection between them.

In order to insulate the wheels 3 from the wheels 23, and the main frame of the car, a construction such as shown in Figure 6 may be employed. Referring to this figure, 16 designates the spindles on which the wheels 3 are journaled, such spindles being secured, as indicated at 16^a, to the ends of 20 guide arms 2, formed of wood or other material of a sufficiently insulating nature to prevent the passage of such low voltage current as is encountered on the track circuit. The usual braces 2^a may also be secured to 25 the wooden arms 2, as shown in Figure 6.

In Figure 3, I have shown the wheels 3 as mounted upon the spindles 16, and have conventionally illustrated, in the usual manner, the fact that these spindles are insulated 30 from the rest of the car. The wheels 23 are mounted upon separate spindles 26, journaled in suitable boxes carried by the frame of the car, in the usual manner.

7 designates a battery mounted on the 35 car, such as is ordinarily used for ignition in connection with the gasoline motor, and to the rear of this battery, I place a panel or instrument board 8, supported on brackets 14, as clearly shown in Figure 1. On this 40 instrument board are preferably mounted two low voltage lamps 9 and 10, two switches 12, two binding posts 13, and an indicating instrument 11, in the nature of an ammeter. The lamps and indicating instrument are 45 connected in multiple between two conductors 16^c and 16^e. The conductor 16^c connects with a wire 16^b, which is secured to the spindles 16 of the wheels 3, while the conductor 16^e is connected with the other wheels 50 23, through the frame of the car.

While I have shown two lamps 9 and 10, it will be understood that only one of these lamps is used at any one time. The two lamps are provided because of the fact that 55 on some sections, a railroad may use direct current of one voltage, and on other sections, alternating current of another voltage, in the track circuit. It will be understood that by opening or closing the respective switches 60 12, either one or the other of the lamps 9 and 10 may be included in the circuit, in accordance with the character of current in the particular block being tested.

Assuming the car thus equipped to be

traversing a block, traveling in a direction 65 away from the end to which the track battery is connected, it will be obvious that current from such battery or other source will flow along one rail 1 up through the wheels 3, conductors 16^b and 16^e, to and 70 through one of the lamps 9 or 10, and the indicating instrument 11, thence through the conductor 16^e, wheels 23, and through the other rail 1^a back to battery. This forms 75 a complete circuit, including the track rails, and one of the lamps 9 or 10 will thus be caused to glow, and the indicating instrument 11 will show a certain strength of current passing through the circuit. As soon, 80 however, as the car passes over a broken or loose connection, or other defect, in either track rail, the above described series circuit is immediately interrupted, and the signal lamp goes out and the pointer of the indicating instrument 11 swings back to zero. The operator will thus be immediately advised of the fact that he has encountered the defect or trouble for which he was testing, and by at once stopping the car, and examining 85 the rails for a few feet back, he will 90 be able to readily locate the fault.

It sometimes happens that the defect is in the nature of a loose or corroded joint, which will permit sufficient current to pass to cause the lamp 9 or 10 to continue to glow, and in such a case, the presence of the defect will be shown by the indicating instrument, the pointer of which will swing back toward zero a distance proportional to the resistance 95 of the loose connection encountered.

In order to make even more positive the 100 operation of my improved testing device, I may and preferably do also equip the car with the apparatus shown in detail in Figure 7, and also conventionally illustrated in Figure 3. Referring to Figure 7, 8^a designates a second panel or instrument board, on which is mounted an electromagnet 17, and a special signal lamp 27. The windings of the electromagnet 17 are connected through a circuit 16^d with the conductors 16^c and 16^e, extending to the wheels at each side of the car respectively. Arranged to 105 cooperate with the electromagnet 17 is an armature 17^a, carried at the end of a lever 18, pivoted at 18^b to the panel board, and provided with a hook or detent 18^a. When the lever 18 is in the horizontal position shown in full lines in Figure 7, this detent is adapted to engage under a shoulder 19^a, formed on a weight 19, arranged to slide freely on a vertical rod 20, held by brackets 21, secured to the panel board. This weight 110 is preferably made of metal, and each end thereof serves as a switch. Adjacent one end of the guide rod 20 is a pair of spaced insulated contacts 22, and adjacent the other 115 end of the rod is a pair of similar contacts 120 125

22^a. When the weight 19 is in its elevated position, as shown in full lines in Figure 7, it engages and bridges the contacts 22^a, and when it is in its lowermost position, as indicated in dotted lines, it engages and bridges the contacts 22.

The contacts 22 are connected by means of a conductor 26, with the lamp 27, and by means of a conductor 25, with the battery 7, so that when these contacts are bridged by the weight 19, a circuit is completed from the battery 7 to the lamp 27.

The contacts 22^a are connected to conductors 22^b, which constitute the ignition circuit extending from the battery 7 to the internal combustion engine, the cylinder of which is indicated at 4^a, and is shown as having a spark plug 4^b, mounted therein. A timer or similar interrupting device 24 is, of course, interposed in the ignition circuit. When the weight 19 is in its elevated position, it bridges the contacts 22^a and thus maintains the ignition circuit in an operative condition, but when this weight moves downward, it opens the ignition circuit at the contacts 22^a.

From the above, it will be obvious that, assuming the car to be traveling in a direction away from the track battery, as above described, current from such track battery will flow through the rails and wheels through the windings of the electromagnet 17, by way of the conductor 16^a, thus maintaining said electromagnet energized, so long as the track circuit is not interrupted. The armature 17^a and lever 18 are thus held in the position shown in full lines, and the detent 18^a sustains the weight 19, in its elevated position, maintaining the ignition circuit closed at the contacts 22^a. When the car encounters a loose connection or other defect in the track circuit, however, the electromagnet 17 immediately becomes de-energized, and releases its armature, the lever 18 thereupon swinging up to dotted line position, and permitting the weight 19 to fall. The falling of the weight performs the two-fold function of opening the ignition circuit at the contacts 22^a, thus immediately stopping the motor, and of closing the lamp circuit at the contacts 22, thus causing the signal lamp 27 to flash up. Thus, the car is automatically brought to a stop at approximately the point where the fault or trouble in the track circuit is encountered, and the defect may then be accurately located, without further trouble.

It will thus be seen that I have provided improved means whereby a fault or defect in the track circuit of any given block may be definitely located, within a few minutes time, and thus extended delays to traffic avoided, and it is thought that the many advantages of my invention will be fully appreciated without further discussion.

What I claim is:—

1. Apparatus for testing the continuity of a track circuit having a source of current connected between the rails thereof, comprising a car adapted to run upon the rails 70 and having the wheels on one side insulated from those on the other side, an electromagnet on said car having one end of its winding connected with the wheels at one side of the car and the other end of its winding connected with the wheels at the other side of the car, whereby said winding is included in a circuit with said source of current, through the rails, a lamp and a battery carried by said car, an electric circuit connecting said battery and lamp and including 75 a pair of contacts constituting a switch, means controlled by said electromagnet, when energized, for maintaining said switch open, and means, operating automatically upon the de-energization of said electromagnet, for forming an electrical connection between said contacts and closing said lamp circuit.

2. Apparatus for testing the continuity 90 of a track circuit having a source of current connected between the rails thereof, comprising a car adapted to run upon the rails and having the wheels on one side insulated from those on the other side, an internal 95 combustion engine for driving said car, an electromagnet on said car having one end of its winding connected with the wheels at one side of the car, and the other end of its winding connected with the wheels at the other side of the car, whereby said winding is included in a series circuit with said source of current through the rails, a battery carried by said car, a circuit for supplying ignition current from said battery to said engine, a switch in said circuit, means controlled by said electromagnet, when energized, for maintaining said switch closed, and means operating automatically, upon de-energization of said electromagnet, for 100 opening said switch, and thus stopping the car.

3. Apparatus for testing the continuity of a track circuit having a source of current connected between the rails thereof, comprising a car adapted to run upon the rails and having the wheels on one side insulated from those on the other side, an internal combustion engine for driving said car, an electromagnet on said car having one end 115 of its winding connected with the wheels at one side of the car, and the other end of its winding connected with the wheels at the other side of the car, whereby said winding is included in a series circuit with said source of current through the rails, a battery carried by said car, a circuit for supplying ignition current from said battery to said engine, a switch in said circuit, a lamp also 120 on said car, a circuit for supplying current 125 on said car, a circuit for supplying current 130

from said battery to said lamp, said circuit including a switch, means controlled by said electromagnet, when energized, for maintaining said ignition circuit switch closed and said lamp circuit switch open, and means operating automatically, upon de- energization of said electromagnet for

simultaneously closing said lamp circuit switch and opening said ignition circuit switch, whereby a signal is given and the car stopped when any break in the continuity of the track circuit is encountered. ¹⁰

In testimony whereof I affix my signature.
ABRAHAM B. BARNETT.
